Primary Examiner — Mary Shannon Malley*Assistant Examiner* — Michelle Marquart Christeon(74) *Attorney, Agent, or Firm* — MATTHIAS SCHOLL P.C.; Matthias Scholl(57) **CLAIM**

The ornamental design for a foldable table, as shown and described.

DESCRIPTION

FIG. 1 is a front elevation view of a foldable table, showing my new design;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a perspective view thereof; and,

FIG. 8 is a perspective view thereof in a folded state.

The broken lines in the drawings depict portions of the foldable table that form no part of the claimed design.

1 Claim, 8 Drawing Sheets(56)
